UNITED STATES PATENT OFFICE.

ALEXANDER M. ALEXANDER, OF BEVERLY, MASSACHUSETTS, ASSIGNOR TO UNITED SHOE MACHINERY COMPANY, OF PATERSON, NEW JERSEY, A CORPORATION OF NEW JERSEY.

KNIFE FOR LEATHER-SKIVING MACHINES.

1,076,934.

Specification of Letters Patent.

Patented Oct. 28, 1913.

Application filed October 16, 1909. Serial No. 522,905.

To all whom it may concern:

Be it known that I, ALEXANDER M. ALEXANDER, a citizen of the United States, residing at Beverly, in the county of Essex 5 and State of Massachusetts, have invented certain new and useful Improvements in Knives for Leather-Skiving Machines; and I do hereby declare the following to be a full, clear, and exact description of the invention, such as will enable others skilled in the art to which it appertains to make and use the same.

This invention relates to a cylindrical knife adapted for use in leather skiving and 15 other machines.

The object of the invention is to provide an improved knife, the blade of which may be readily adjusted to compensate for wear occasioned by grinding the same, or may be 20 readily removed and replaced by a new blade when worn out.

With this object in view a feature of the invention contemplates the provision of a holder for exteriorly supporting the blade 25 to give it the required rigidity, and means for moving the blade axially of the holder to enable the blade to be accurately and readily adjusted.

A further feature of the invention contemplates the provision of a holder for exteriorly supporting the blade, means for moving the blade axially of the holder, and means for clamping the blade against the 30 holder to securely hold the blade in position 35 and insure a true cylindrical blade.

In addition to the features of invention above referred to, the present invention also consists of certain novel features of construction and arrangement of parts hereinafter 40 described and claimed, all of which will be obvious to those skilled in the art from the following description.

The several features of the invention will be clearly understood from an inspection of 45 the accompanying drawing, in which—

Figure 1 is a front elevation of the knife, and Fig. 2 is a sectional elevation of the same with parts broken away.

As shown in the drawings, the blade 1 of 50 the knife is formed from a thin flat band of steel which is bent into the shape of a cylinder and has one edge sharpened. For the purpose of adjusting the blade axially, a ring 3 is provided which is recessed at its 55 outer edge to receive the blade. The ad-

justing ring 3 is preferably provided with pins 4 which are received in bayonet slots 5 formed in the inner edge of the blade. In the present instance three slots are provided, one adjacent each end of the blade strip and 60 one midway of its length. By this construction the blade 1 may be readily attached to and detached from the ring 3, and this ring acts as a carrier whereby the blade may be adjusted inwardly as well as outwardly, although it will be understood that a ring or other suitable means may be employed which merely operates to move the blade outwardly. The ring 3 is interiorly 65 threaded to fit the threaded exterior of a head 8 which is secured by bolts 9 to a flange 10 formed on the shaft 12. The blade 1 is supported exteriorly by a cylindrical cup-shaped holder 14 which is rotatably mounted upon the inner reduced portion 70 of the head 8 and also fits the external periphery of the adjusting ring 3.

It is desirable to support the blade interiorly and clamp it in adjusted position against the interior of the holder 14 to produce a true cylindrical blade and hold it firmly in place while being rotated at a high rate of speed. This is accomplished by a clamping ring 16 mounted to rotate about the outer end of the head 8 and provided 80 with a series of radial slots 17 extending from its periphery toward the center to divide the ring into a corresponding number of yielding sectors 18. The outer surface 19 of the ring 16 is concave and operates to 85 eject loose chips and dust under centrifugal action, thus keeping the interior of the knife free from chips. Bolts 20 pass through the holder 14 and adjusting ring 3 and are threaded into the sectors 18. Thus 90 the holder, adjusting ring, and clamping ring 16 are held against relative rotation and by tightening the bolts 20 the holder and clamping ring are clamped against the head 8, and the sectors 18 are sprung outwardly against the interior of the blade 1 to 95 clamp the latter against the holder. 100

For adjusting the blade, the bolts 20 are unscrewed sufficiently to free the blade from the clamping ring and enable the holder and clamping ring to be rotated about the head 8. Then by holding the shaft 12 stationary and rotating the holder, adjusting ring and clamping ring, the adjusting ring and the blade are moved axially of the holder by the 110

threaded engagement of the adjusting ring with the head 8. After the blade has been thus adjusted the bolts 20 are tightened to clamp the holder upon the head and the 5 blade within the holder.

To remove the worn out blade and replace it with a new blade, the screws 20 are removed from the clamping ring 16 and the clamping ring is removed from the interior 10 of the holder. The adjusting ring is then unscrewed from the head 8 and the blade 1 removed from this ring. A new blade is then slipped on the ring 3 with the pins 4 entering the bayonet slots 5, the ring is then 15 screwed on to the head 8, and thereupon the clamping ring is placed upon the head and clamped in position by the bolts 20.

Although the blade is shown and described as formed from a flat band of steel 20 bent in the shape of the cylinder and retained in this shape by the holder 14, it will be understood that the blade may be formed of an integral cylindrical shell.

The invention having been described, 25 what is claimed is:—

1. A knife for skiving machines, having, in combination, a cylindrical blade, a cylindrical holder within which the blade fits, an interior supporting ring fitting within the 30 blade, a head upon which the holder and ring are rotatably mounted, an adjusting ring engaging a screw-thread on the head, and devices for securing the holder, rings and head against relative rotation, substantially as described.

2. A knife for skiving machines, having, in combination, a cylindrical blade, a cylindrical holder within which the blade fits, an interior supporting ring slotted to form 35 expandable sectors, means for effecting axial adjustment of the blade relatively to both holder and ring, and devices for springing the sectors outward to clamp the blade.

against the interior of the holder, substantially as described. 45

3. A knife for skiving machines, having, in combination, a cylindrical blade, a cylindrical holder within which the blade fits, means for adjusting the blade and an interior clamping ring fitting within the blade 50 and formed with sectors arranged to be forced outwardly to clamp the blade against the holder, substantially as described.

4. A knife for skiving machines, having, in combination, a cylindrical blade, a cylindrical holder within which the blade fits, a clamping ring fitting within the blade and slotted to form sectors, a blade adjusting ring within the holder back of the clamping ring, bolts connecting the holder and 55 clamping ring and passing through the adjusting ring, a head on which the holder and clamping ring are rotatably mounted, provided with a screw-thread engaged by a screw-thread within the adjusting ring, substantially as described. 60

5. A knife for a leather skiving machine, having, in combination, a holder, a blade, and means for clamping the blade to the holder so shaped as to eject the chips 70 through the front of the knife, substantially as described.

6. A knife for skiving machines, having, in combination, a knife blade, an adjustable knife carrier to which the knife blade is 75 detachably connected, a plurality of retaining members on opposite sides of the blade for retaining the blade on the carrier, and means for moving the carrier relatively to the retaining members to adjust 80 the blade as the blade is worn away.

ALEXANDER M. ALEXANDER.
